UNITED STATES PATENT OFFICE.

JOSEPH L. SMITH, OF DENVER, COLORADO.

DENTAL PASTE.

No Drawing.

Application filed June 30, 1923. Serial No. 648,801.

To all whom it may concern:

Be it known that JOSEPH L. SMITH, a citizen of the United States, residing at Denver, in the county of Denver and State of Colorado, has invented certain new and useful Improvements in Dental Paste; and he does hereby declare the following to be a full, clear, and exact description of the invention, such as will enable others skilled in the art 10 to which it appertains to make and use the same.

This invention relates to an improvement in dental paste, and more particularly in a paste suitable primarily for temporary fillings adapted to correct and reduce hypersensitivity in cavities, but also useful and efficient as a protection for teeth against abrasion and chemical action ordinarily incident to and resulting from the affixing and 20 use of plates and other removable parts adapted for attachment to the teeth.

An object of the present invention is to provide a paste of the general character indicated, having the properties of very slow 25 solubility and the proper consistency at normal mouth temperatures.

A further object is to provide a paste of the class described, of such quality and consistency as to adapt it for use and make it 30 easy of application by the patient without expert dental assistance.

A further object is to provide a paste of the class described, which will have the proper consistency for use in the mouth and 35 at the same time a consistency which will make it practicable for use in the ordinary collapsible tube.

Other objects will appear in the following specification.

40 Beeswax has heretofore been used in temporary fillings, but at normal temperatures is undesirably hard for the purposes of the present invention.

45 Paraffin has also been heretofore used, but is of an undesirable quality and consistency when mixed with the other necessary ingredients to make it adaptable for the above mentioned purposes, unless mixed with petroleum jelly or similar substance, 50 and if mixed with such substance paraffin is too readily soluble to make a really satisfactory paste for the purposes served by the present invention.

In accordance with the present invention

a petroleum product such as petroleum jelly 55 is combined with beeswax in proportions determined by the particular objects in view, it having been discovered that the combination of the petroleum product with the beeswax softens the texture of the beeswax at 60 normal mouth temperature and produces a very superior medium susceptible only to slow dissolution in association with the remedial agents used.

For the purpose of a dental paste adapted 65 to the uses previously indicated it has been found that a combination of the beeswax with the petroleum product above indicated in association with sodium bicarbonate, sodium baborate, and calcined magnesia gives 70 very desirable results. A specific formula of demonstrated efficiency consists of:—Sodium bicarbonate 2 parts, sodium baborate 1 part, calcined magnesia 1 part, petroleum jelly 3 parts, wax 1 part.

In this paste the sodium bicarbonate operates to neutralize acids in the mouth and to prevent fermentation with the resultant formation of acids. The sodium baborate operates to prevent the discoloration of the 80 teeth by the sodium bicarbonate, which otherwise has a tendency to produce a brownish discoloration. The calcined magnesia is also slightly anti-acid, but is chiefly useful in reducing sensitiveness.

Having thus fully described my invention, what I claim is:—

1. A vehicle for temporary tooth fillings and the like comprising beeswax and a substance having the characteristics of petroleum jelly.

2. A vehicle for temporary tooth fillings and the like comprising beeswax and petroleum jelly.

3. A vehicle for temporary tooth fillings 95 and the like comprising beeswax 1 part and petroleum jelly 3 parts.

4. An improved temporary tooth filling and the like comprising beeswax, petroleum jelly, sodium bicarbonate, sodium baborate 100 and calcined magnesia.

5. An improved dental paste consisting of beeswax 1 part, petroleum jelly 3 parts, calcined magnesia 1 part, sodium baborate 1 part, and sodium bicarbonate 2 parts.

105 In testimony whereof I affix my signature.

JOSEPH L. SMITH.
